[57] CLAIM

The ornamental design for extendable scraper, as shown and described.

DESCRIPTION

FIG. 1 is an exploded view of the two components of extendable scraper showing my new design in its most extended form;

FIG. 2 is a front elevational view thereof in the extended form with components connected;

FIG. 3 is a rear elevational view thereof;

FIG. 4 is a side elevational view thereof;

FIG. 5 is a side elevational view thereof; and,

FIG. 6 is a top plan view thereof, the side opposite being a mirror image of the side shown in FIG. 6.
